UNITED STATES PATENT OFFICE.

MARCUS B. BEHRMAN, OF NEW YORK, N. Y., ASSIGNOR TO THE LOX SEAL CORPORATION, OF BROOKLYN, NEW YORK, A CORPORATION OF NEW YORK.

PACKAGE AND CLOSURE THEREFOR.

Application filed March 27, 1925. Serial No. 18,775.

My present invention relates generally to improvements in packaging and involves the method and means for securing a package or container in closed condition and coordinate-
ly involves the method and means for securing the members of a closed container or package against separation.

My invention further involves an arrangement whereby a container of this character can have its elements arranged in the form of sheets cut to predetermined shape and size, which elements can then be shaped or folded for assembly immediately prior to use.

Merchants who do a credit or exchange business find that it is a common practice for a prospective customer to order up merchandise and after making use of or otherwise handling the contents to then return the merchandise for credit or exchange, and my invention has particular utility to prevent such practice occurring without detection. Its utility, however, extends generally to the field of packages and containers and of maintaining the package or container closures in predetermined position, and certain phases of my invention may serve even a broader field of utility.

One of the objects of my invention is the provision of an arrangement whereby a container closure can be associated with the container against accidental removal and then affixed thereto so that the closure member cannot be removed without detection.

Another object of my invention is the provision of an arrangement whereby the means for securing the closure against removal can also serve to reinforce and brace the box against distortion and breakage.

A still further object of my invention is the provision of a simple and inexpensive means which on the one hand permits of rapidly fastening receptacles, containers or the like and on the other hand insures against opening of the receptacle or tampering with the contents thereof and which therefore provides a means for detecting the breach of a specific provision against such acts imposed by the merchant upon the prospective customer where return is requested.

Containers of the type in which the box elements are in the form of sheets, which are folded to form the box parts are generally provided with arrangements for maintaining the box parts in their shaped or folded con-

dition. Another object of my invention is the provision of an arrangement for maintaining box parts in its shaped or folded condition and more particularly, the provision and arrangement for such purpose of fastening and which not only maintain such box part in such condition, but also serve to hold the box parts together so as to maintain the receptacle or container in a closed condition. A still further object of my invention is the provision of fastening elements of such a character that they coact with the box parts not only to maintain them associated together but also permit of their being sealed together so as to prevent any separation of the parts without detection.

For the attainment of these objects and such further objects as may hereinafter appear or be pointed out, I have illustrated embodiments of my invention in the accompanying drawings wherein—

Fig. 1 shows in perspective one embodiment of my invention;

Fig. 2 is a horizontal section taken on line 2—2, of Fig. 1;

Fig. 3 is a section taken on line 3—3 of Fig. 1 showing the use of modified form of holding means;

Fig. 4 is a perspective view of another embodiment of my invention in which the cover is received on the inside;

Fig. 5 shows a blank from which the bottom of a modified form of container is to be formed by a folding operation;

Fig. 6 is a broken away view of the blank of Fig. 5 partly folded to form the bottom of the box;

Fig. 7 is a fragmentary view of sufficient of the top and bottom blanks of the embodiment of Fig. 5 folded and ready to be associated to form the closed container;

Fig. 8 is a fragmentary view of the container of Fig. 7 completely assembled and locked;

Fig. 9 is a perspective view of the fastener element employed in Fig. 7.

Fig. 10 and 11 show the blanks from which the side wall structure and either the top or bottom of a knock-down embodiment of my box can be formed for assembly;

Fig. 12 is a perspective view of a container partly formed of the blanks of Figs. 10 and 11;

Fig. 13 is a horizontal section through one corner of the lower end of the embodiment

of Fig. 12 to show the manner of associating the tie or tackle member with said embodiment.

Fig. 14 shows a blank from which the fasteners of the embodiment of Fig. 12 are formed;

Fig. 15 is a perspective view of such fastener after it has been formed for use; and

Fig. 16 is a view similar to Fig. 13 showing a modified manner of associating the tie or tackle member with this embodiment.

In the embodiment of Fig. 1, I show a receptacle container 11 having side walls 12 illustrated as integral with the bottom, 15 and a cover or closure member 13 illustrated as having the depending continuous flange 14 arranged to be positioned adjacent to and overlapping the side walls 12 on the outside. The container may be made of a regularly 20 distortable material such as fibre board.

Upon viewing Fig. 2 of the drawing, it will be observed that I provide the upstanding walls 12 of the container with a plurality of members 15 preferably formed of 25 metal and secured thereto in any preferred or desired manner and each having the lip 16 projecting outwardly therefrom and each member 15 having an opening or perforation 17 therethrough as shown in Fig. 1. 30 The walls 12 may be provided with as many of these members 15 as may be found convenient or necessary, four being illustrated in the embodiment of Fig. 1 one for each wall. The depending flange 14 of the cover member 13 is provided with slots 18 so positioned and of such a size that when the cover is placed in its container closing position as shown in Fig. 1, each one of these slots 18 will register with one of the projecting lips 40 16 and due to the distortability of either the cover member or the body member or both, the members 16 can be caused to pass through the slots 18 and project therebeyond as shown in Figs. 1 and 2 for a sufficient distance to expose the openings 17.

The engagement of the elements 16 with the cover member as shown in Fig. 1 will hold the cover against accidental removal and to seal the closure against removal without detection, I pass through each of the 50 openings 17 in the member 16, the flexible shackle or tie 19 each end of which is provided with the anchoring tip 20 formed so that the diameter or thickness thereof is disproportionately less than the length, with the 55 flexible tie or shackle 19 attached to the tips so that the effect of the fastening point is intermediate the ends of the tip 20, one end 20' of the tip being preferably formed 60 so as to serve as a guiding or piercing portion and the other end 20" forming a handle portion. The tips 20 are then each passed through the opening 21 into the cavity in the seal 22 which is enlarged within its interior to receive the tip in transversely ar-

ranged position. This opening 21 is wide enough to permit of the passage therethrough of the tip 20 when moved longitudinally thereof, but is narrower than the width of the tip so that when the tips 20 are inserted in the seal 22 as described, any pull upon the shackle will automatically position the tips 20 transversely of the seal 22 so as to prevent the removal of the tips therefrom.

It will thus be seen that the cover of the box is not only held in position on the container by the member 16 but is locked and sealed in such position by the tie member 19 and the seal 22 so that the cover 80 cannot be removed without detection, because such removal will require the destruction of either part of the container or of the tie member.

The tie member 19 is made no longer than 85 is absolutely necessary to permit of its being passed all the way around the box with the tips 20 secured within the seal 22 so that the tie 19 serves not only the securing and sealing purposes already described, but also 90 serves to brace the box against undue bulging or distortion.

In Fig. 3 of the drawing, I show the slightly modified form of the fastener used in the embodiment of Figure 3 and in which 95 the members 15' are made of length of sheet material such as wire doubled over so as to provide the eye 16', the ends of the strip 15" being bent in opposite directions against the inner surface of the container, the wall of 100 the container being received between these ends 15" and the widened inner or seat portions 16" of the eye 16'.

A container constructed to receive the cover within the outlines thereof so that no 105 portion of the cover projects or extends beyond the walls of the container, possesses certain advantages and in Fig. 4, I show an embodiment of my invention in which the cover is so secured and upon viewing this figure, it will be observed that the cover 30 is provided with a continuous upstanding wall 31 and is so dimensioned as to fit snugly within the walls 32 of the container 33. The walls of the container are provided with 110 openings 34 through which are received the members 35 carried by walls of the cover and in the projecting portions 36 of the members 35, there are provided the openings 37 through which is passed securing means 115 such as a shackle 19 with tips secured or the seal 22 as already described in connection with embodiments of Fig. 1.

In Fig. 4 of the drawing, I have illustrated a further embodiment of the securing 120 and sealing means which may serve either as alternative arrangement for that already in connection with this figure or as supplemental thereto. This embodiment comprises a short shackle 38 passed around the 125

outside of each corner of the box with tips 20 (not shown) passed through the registering openings, 39, 39 on opposite sides of, and adjacent each corner of both container 5 and cover with the tips 20 forced through the top 30 of the cover member, the shackle 38 being just long enough to permit of these tips being forced through. It will be understood from the description given in connection with Fig. 1 that when the tips are forced through the base 30 of the cover, which as stated may be fibre board, that the tips will then position themselves so as to prevent their withdrawal. The tips 20 employed in this embodiment may have their ends 20' pointed so as to permit of their being forced through the side walls of the container and of the cover and then through the bottom or body wall of the cover or 20 where desired, the box in the cover can be provided with predeterminedly positioned openings so as to permit of the tips being passed through.

In Figs. 5, 6, 7, 8 and 9, I show an embodiment of my invention particularly intended for the lighter weight boxes such as are generally employed for the packaging of suits, dresses, cloaks, etc. and in which I employ a construction of a "knock down" 30 type, that is of a type where the box parts which generally are the bottom and the top, are each supplied in sheet form and scored so as to permit their being folded to provide the bottom and side wall structure, and in 35 which the blanks are adapted to be folded immediately prior to the packaging of the goods, and in Fig. 5, of the drawing, is shown a blank from which the bottom 80 is formed.

40 It will be observed that this blank of Fig. 5 is scored or otherwise weakened parallel to each edge along the lines 81 and at an angle thereto along the lines 82 from the point at which the parallel scores cross each other to each corner of the blank.

The blank is further provided adjacent each corner with the three predeterminedly positioned and dimensioned elongated slots 83, 84 and 85, one of the slots of each group 50 being positioned substantially at right angles to the other for reasons that will be understood.

55 In the formation of the bottom of the box bottom 80 from the blank of Fig. 5, I fold the box along each of the score lines 81 for the full length of each score line and then fold each corner of the box along the score line 82 so as to provide the four upstanding walls of the container body of which three, 60 86, 87, and 88 are shown in Fig. 6 of the drawing and the triangular superposed portions 89, 90 at each corner which are then folded down upon the outside of the adjacent wall, the complete folding being 65 shown in the upper corner of Fig. 6 and

the partial folding in the lower corner of said figure.

This manner of folding the blank will cause the elongated slots 83, 84 and 85 to register with the longest dimension presented vertically as shown in Fig. 7 of the drawing so as to provide the vertically positioned slot 91 adjacent each corner of the bottom of the container.

I preferably employ a fastener of the character such as shown in Fig. 9 for holding the box bottom in its folded condition and upon viewing this Fig. 9, it will be observed that this fastening element is made of sheet metal and preferably of a metal stamping bent so as to provide the eye or head portion 93, the neck 94 and the feet or abutment members 95. The width of the head and neck portion 93 and 94 is such as to permit them to pass through the elongated slot 91 (see Fig. 7) only when the head portion is positioned vertically, that is, with its longest dimension parallel to the longest dimension of the slot 91 and the length of the head or eye portion 93 is materially greater than its width.

The fastener of Fig. 9 having been passed through the slot 91 as described, is then given a 90° rotation so as to cause the head 93 to be positioned horizontally, and transversely of the slot 91 thus locking the fastener in position against accidental removal and also thereby locking the parts in folded position against accidental separation.

A blank similar to that of Fig. 5 is employed for forming the cover member 99 except that the slots in the cover blank which correspond to the slots 83, 84 and 85 are so arranged that when the cover member is fully folded and formed, the slot 100 through said member adjacent each corner thereof formed by the registration of these slots and corresponding to the slot 91 in the bottom member will be positioned generally horizontally as shown in connection with the cover member of Figs. 7 and 8 of the drawing.

It will also be understood that should there be any difference required in the dimensions between the blanks of the cover member and the bottom member, because of the fact that one is placed outside of the other, that provision can be made for this in cutting and scoring the blanks.

When the top member is folded exactly in the same manner as is the bottom member already described, the two are associated merely by telescoping the top member over the bottom member and the slot 100 adjacent each corner of the top member is preferably of the same dimensions as is the slot 91 adjacent each corner of the bottom member except that it is positioned at right angles thereto, so as to cause it to register with the horizontal position in which the

fastener has already been placed as described, and as shown in connection with the bottom member in Fig. 7. This permits of the slot 100 being passed over the head 93 of the fastener, upon which the fastener is again given a 90° rotation to its vertical position to lock the two members together with the members locked together, I now pass through the eyes 93 of each of the four locking members employed, a tackle 19 secured and sealed by seal 22 as already described in connection with Figs. 1 and 4.

The parts 96 of the eye or head portion 93 are preferably made flat and are positioned at such a distance from the feet or abutment members 95 as to snugly receive therebetween the superposed layers 87, 90 and 91 of the bottom and the corresponding layers of the tops so as to permit of a little looseness as possible at this point. The feet or abutment members 95 as shown in the drawings are made much wider than the slots 91 and 100 so that under no circumstances can it be passed through the head and in Fig. 9, I show these feet as preferably being semi-circular because as will be understood when a rotation is given to this fastener of Fig. 9, after the garment is secured within the container, the liability of any sharp edge on these feet catching and tearing the garment will be reduced to a minimum, if not wholly eliminated.

In Figs. 10, 11 and 12, I show a further embodiment of my invention in which I employ a more sturdily constructed knock-down type. The blank 40 of Figure 10 is preferably scored or otherwise weakened for folding along the lines 41, 42, 43 and 44 so as to provide the sections 45, 46, 47, 48, 49. Each of these sections is provided adjacent its upper and lower edges with the group of horizontally extended slots 50. One slot at the top and one slot at the bottom is illustrated as being employed for each section of the side wall structure, and preferably positioned midway of the tops of the sections, although as will be understood later, it is not necessary that all of these sections be slotted or that each be provided with but one slot 50 at the top and one slot 50 at the bottom.

The sections 45, 46, 47, 48 and 49 are further each provided both at the top and at the bottom with openings 50' positioned adjacent the lines of fold 41, 42, 43 and 44 thus providing the end sections with but one opening at the top and one at the bottom and the other sections with two such openings at the top and two such openings at the bottom. As will be observed upon viewing the drawings, whereas, the group of openings 50 are preferably horizontally elongated, the group of openings 50' need not be elongated, for reasons that will be understood later on.

When the blank of Fig. 10 is folded along the lines 41, 42, 43, and 44 so as to have each of the sections at right angles to the adjacent ones, there is provided the side wall construction of the container as shown in Fig. 12 of the drawing in which the section 46 forms the wall 46', the section 47 forms the wall 47', and 48, the wall 48' and the sections 45' and 49' form the fourth wall 49' of the container body. The openings 50 at the top of the sections 45 and 49 are so arranged that when the blank of Fig. 10 is bent to form the side wall 49' of Fig. 12, these openings will be in substantial registry and the same is true of the openings 50 adjacent the bottom of these sections.

The blank of Figure 11 which is to form the top is provided with a body section 51 and four projecting flanges 52, 53, 54 and 55, two of the opposite flanges namely 52 and 54 being each provided with the lips or extensions 56 and 57. The cover member which is shown in Fig. 12 as partly completed, is formed from this blank of Fig. 11 by bending the flanges 52, 53, 54 and 55 substantially at right angles to the body member 51 along the lines 59, 60, 61 and 62 which bending operation may be made easy and along definite lines by a scoring or otherwise weakening the blank along these lines and the lips or extensions 56 and 57 of the flanges 52 and 54 are bent at right angles thereto and superposed upon the adjacent side walls of the cover formed by the flanges 53 and 55 as shown in connection with the flanges 52 in Fig. 12.

The flanges 52, 53, 54 and 55 are each provided with an elongated opening 58 substantially of the same size as the slots 50 already described as employed in the side wall construction adjacent the top and so positioned as to cause them to register with these openings 50 when the cover is inserted within the upper end of the container as already described in connection with my embodiment of Fig. 4. The lips 56 and 57 of each of the flanges 52 and 54 are further each provided with the opening 65 so positioned and arranged as to cause them to register with the openings 66, formed adjacent each end of each of the flanges 53 and 55 when the flanges are bent down and the lips superposed upon the adjacent flanges to form the cover construction shown partly completed in Fig. 12.

The flanges 52 and 54 are further each provided with the openings 67 formed adjacent each end, the purposes of all of which will be understood as this specification is read.

In Fig. 14 of the drawing, I show a blank from which I form the member to secure the cover to the body and which functions somewhat as does the element 15 in Fig. 1 and which is constructed similarly to the blank

of Figure 9. This blank 70 is preferably in the form of a strip of metal stamped out so as to provide the neck or web portion 71 and the two head or shoulder portions 72 much larger than the connecting web 71 and this blank is bent and shaped so as to form, the construction 73 shown in Figs 15 wherein there is formed the head or eye portion 74, the neck 75 and the two oppositely directed feet 76.

For an understanding of the manner in which the cover is associated with the body of the container, I will state that the bottom blank is in all respects a duplicate of the top blank of Fig. 10 and is folded, and assembled with the bottom of the body member to form the bottom closure in all respects as the top cover is formed the blank of Fig. 11, and it will therefore be understood that the description of the top cover member and its manner of assembly applies equally well to the bottom cover member. Therefore in this description of one, reference is frequently made to the other.

When the cover blank of Fig. 11 is bent to form the box cover as shown in partly completed form in Fig. 12, this cover member is inserted within the container substantially in the same way as the cover 30 is inserted within the container of Fig. 4. It will be understood that the openings or slots 58 in the side walls or flanges of the cover member 51 will register with the openings 50 adjacent the top of the wall members and registering openings 65 and 66 and the openings 67 in the flanges 52, 53, 54 and 55 upstanding from the cover 51 will all register with corresponding openings 50' located on opposite sides of each corner at the top of the box structure.

The metal fastener 73 of Fig. 15 is then inserted through the registering openings 50 and 58 in the box cover and box body, the dimensions of the slots 50 and 58 being such as to permit the head or eye-portion 74 to pass therethrough only when the head is presented horizontally and this head 74 is then turned through 90° so as to position it vertically as shown at the bottom of Fig. 12. In this position, not only does the head serve to lock the cover in position, but the openings through the eye or head portion thereof are all presented in a common horizontal plane.

The superposed flanges of the cover and the walls of the box or container are held between the feet 76 of the fastener which are directed oppositely as shown in Fig. 15 and are positioned adjacent the inside face of the box container wall and the elongated head or eye portion 74, the slots 50 and 58 being positioned so as to permit of the rotation of these feet 76 of the fastener as already described.

A tackle 19 having tips 20 of the char-

acter described in connection with the embodiment of Fig. 1 is then threaded alternately through the eye 77 of the head 74 of the fasteners and through the groups of registering openings on opposite sides of each corner of the box as shown more clearly in Fig. 13 of the drawing and the tips 20 of the tie member 19 are then secured in a seal or other fastener 22 substantially as described in Fig. 1.

In Fig. 16 of the drawing, I show a still further embodiment of my invention in which the cover is received within the top of the box as in the embodiment of Figs. 4 and 12 with the fastener however reversed so as to present the eye portion thereof within the outlines of the box and in this figure, I have illustrated this embodiment as employing the knockdown construction of Fig. 12 although as will be understood, it can equally well be employed with the preformed construction of Fig. 4. The fastener elements 73 are passed through the registering openings 50 and 58 in a reversed direction from that described in connection with Fig. 12 so that the oppositely directed feet 76 are positioned on the outside of and in contact with the outer surface of the side walls of the container body and the head or eye portion 74 is presented on the inside.

The tackle or tie member 19 is threaded through the eye members and the registering openings 50', 65, 66 and 67 adjacent the corners in a reversed direction from that described in connection with Fig. 12 so as to have the tackle 19 embrace the corners of the box as shown in this figure, the major portion of the tackle or tie member however, being positioned on the inside and within the walls thereof.

Having thus described my invention and illustrated its use what I claim as new and desire to secure by Letters Patent is—

1. A box construction comprising a knock-down body, fastening means for retaining the body in set-up condition, said means comprising rotatable studs designed to pass through certain portions of the body and to retain the body set up after rotation thereof, and a closure provided with slots which are engageable over said studs only after the latter have been so rotated.

2. A box construction comprising a knock-down body, fastening means for retaining the body in set-up condition, said means comprising rotatable studs designed to pass through certain portions of the body and to retain the body set up after rotation thereof, and a closure provided with slots which are engageable over said studs only after the latter have been so rotated, said studs being so constructed and arranged that further rotation thereof will thereupon lock the closure to the body.

3. A box construction comprising a knock-

- down body, fastening means for retaining the body in set-up condition, said means comprising rotatable studs designed to pass through certain portions of the body and to 5 retain the body set up after rotation thereof, and a closure provided with slots which are engageable over said studs only after the latter have been so rotated, said studs being so constructed and arranged that further 10 rotation thereof will thereupon lock the closure to the body, and a tie member engageable with said studs after the closure is locked to prevent a retractive rotation of the studs.
- 15 4. A box construction comprising a knock-down body, fastening means for retaining the body in set-up condition, said means comprising rotatable studs designed to pass through certain portions of the body and to 20 retain the body set up after rotation thereof, and a closure provided with slots which are engageable over said studs only after the latter have been so rotated, said studs being so constructed and arranged that further 25 rotation thereof will thereupon lock the closure to the body, and a tie member engageable with said studs after the closure is locked to prevent a retractive rotation of the studs, said tie member being provided 30 at its ends with means for connecting said ends in an irremovable manner.
5. A box construction comprising a knock-down body, fastening means for retaining the body in set-up condition, said means comprising rotatable studs designed to pass through certain portions of the body and to retain the body set up upon rotation of the studs, each stud having an eyeleted head; and a closure provided with slots which are 35 engageable over said stud heads only after the studs have been rotated as aforesaid, said studs being so constructed and arranged that further rotation thereof will thereupon lock the engaged closure to the body and 40 also position the studheads with the eyelets in alignment, and a tie member threadable through said aligned eyelets for preventing retractive rotation of the studs.
- 45 6. A box construction comprising a knock-down body which includes superposed layers of material and wherein continued superposition retains the body in set-up condition, fastening means for retaining said layers in superposition, said means comprising rotatable studs designed to pass through said superposed layers and to lock the latter in superposition when the studs are rotated, and a closure designed to telescope the body and provided with slots which are engageable over said rotated studs, the latter being so constructed and arranged that further rotation thereof will thereupon lock the engaged closure to the body.
7. A box construction comprising a body 50 having superposed layers of material pro- vided with registering slots, a closure designed to telescope the body and provided with slots which register with the body slots at an angle thereto, and a rotatable stud for each set of slots, said stud having an elongated head adapted to pass through the slots when it is aligned therewith but not otherwise, whereby rotation of the stud after passage of the head through the body slots will retain the body layers in superposition, and whereby the head, by such rotation, may be brought into proper position for passage through the registering closure slot.
8. A box construction comprising a body having superposed layers of material, said layers being provided with a set of registering slots, a set of studs removably applicable through said slots and adapted upon rotation to retain said layers in superposition, each stud having a medial shank, a laterally enlarged base, and a laterally enlarged head having an eyelet, whereby upon said rotation of the studs the superposed layers are securely held between the bases and heads, a closure having slots which are so positioned and constructed as to engage over said heads only after said rotation, and a tie element threaded through the eyelets to prevent a withdrawal of both the closure and the studs.
9. In a box construction, a body, a closure, said body and closure having registering openings, a set of rotatable studs for removable applications through said openings, said studs being so constructed and arranged that rotation thereof will lock the closure to the body, and means engageable with the rotated studs for preventing removal thereof despite any possible further rotation thereof.
10. In a box construction, a body, a closure, said body and closure having registering openings, a set of rotatable studs for removable application through said openings said studs being so constructed and arranged that rotation thereof will lock the closure to the body, and a tie element engageable with the rotated studs for preventing removal thereof despite any possible further rotation thereof.
11. In a box construction made of sheeted material bent along fold lines to form bottom and side walls, having excess material bent to overlap the side walls, and having aligned elongated slots through said overlapping portions, fastening elements extending through said slots and adapted to lock said overlapping portions against displacement by a partial rotary movement, a closure similarly formed and having its overlapping portions slotted to receive said fastening elements and adapted to be held in position by a further partial rotary movement of the fastening elements, and sealing means comprising a flexible tie element engaging with successive fastening elements and provided

at its terminal ends with locking toggle members.

12. A box construction comprising a body having a slot in a wall thereof, a closure 5 designed to telescope the body and provided with a slot which registers with said body slot at an angle thereto, and a separately applicalbe rotatable stud having a head which is so shaped as to be passable through 10 each slot when it is aligned therewith but not

otherwise; whereby rotation of the stud after passage of its head through the body slot will preliminarily associate the stud with the body, and whereby said head, by such rotation, may be brought into proper 15 position for passage through the closure slot.

In witness whereof, I have signed this specification, this 20th day of March, 1925.

MARCUS B. BEHRMAN.
